CHARLES F. WEST, OF BOSTON, ASSIGNOR TO J. F. TAPLEY AND COMPANY,
OF SPRINGFIELD, MASSACHUSETTS.

Letters Patent No. 79,927, dated July 14, 1868.

IMPROVEMENT IN PAPER-RULING MACHINES.

The Schedule referred to in these Letters Patent and making part of the same.

TO ALL WHOM IT MAY CONCERN:

Be it known that I, CHARLES F. WEST, of Boston, in the county of Suffolk, and State of Massachusetts, have invented certain new and useful Improvements in Paper-Ruling Machines; and I do hereby declare that the following, taken in connection with the drawings which accompany and form part of this specification, is a description of my invention sufficient to enable those skilled in the art to practise it.

The invention relates particularly to the construction and arrangement of mechanism for gauging the length of lines ruled upon the paper, or for automatically carrying the pens into and out of action with the surface of the paper at proper times, or in accordance with the length of lines desired, and the location of these lines upon the paper.

My improvement is mostly in the form of an adjunct, having no direct connection with the ruling-mechanism, but being attached to a ruling-machine, on one side of the frame thereof, so as to leave the ruling-mechanism free from obstructions.

My invention consists primarily in combining, with a ruling-machine, a rotary gauge-wheel, placed on one side of the machine, and at the end of and preferably moved by frictional contact with the ruling-cylinder, said wheel having adjustable surfaces for throwing the pens out of and down into contact with the paper at fixed times, and to rule fixed lengths of lines, there being also combined directly with said wheel a stop-and-latch mechanism, which holds or causes the pens to be held in elevated position, or out of action, after one sheet has passed from under the pens, until such time as that the wheel shall be automatically released from this latch-mechanism, when the wheel will again rotate, and throw the pens into and out of action, according to the lines to be made, and breaks or spaces to be left unruled, in line with each pen.

The drawings represent, at—

Figure A, a plan, at

Figure B, a side elevation, and at

Figure C, a vertical section of a ruling-machine, or parts of such machine, embodying my invention, the section at fig. C being taken on the line *x x*.

a denotes the frame of the machine, in which is mounted the large ruling-cylinder or bed *b*, around which cylinder, and a roll, *c*, the endless-feed apron *d* extends, the sheets of paper to be ruled being carried by this apron, under a grooved roll, *e*, and under cords *f*, passing around this roll and a roll, *g*, and each sheet being ruled as it passes over the roll *b*, (down to the surface of which it is held by the cords *f*.) by a series of pens projecting from a pen-beam, *h*, (one of such pens being seen at *i*.) the machine, in general construction, organization, and mode of operation of these parts, not necessarily differing from machines in common use.

The pen-beam *h* is hung upon standards *k* by journal-pins *l*, and its pens are held down towards, and at proper times against, the sheet of paper beneath, by weights or by suitable springs *m*. On one side of the frame *a*, and in line with the ruling-cylinder, is a table or extension, *n*, upon which is supported a horizontal rotary wheel, *o*, which is directly mounted upon a vertical pin or shaft, *p*, projecting from a slide, *q*. The peripheral surface or tread, *r*, of this wheel rests against the end, *t*, of the cylinder *b*, being pressed up thereto by a spring, *u*, acting against the slide *q*, the pressure being such that the rotation of the cylinder effects (by frictional contact) the rotation of the wheel.

In the upper surface of the wheel *o* is a deep circular groove, *v*, made to receive a series of segmental lifter-pieces, *w*, which may be adjusted in position along in the groove, and may be fixed in any position by screws *x*, or by other suitable devices, the upper edge of each piece *w* projecting above the adjacent surface of the wheel, as seen at fig. B.

Fixed to one end of the pen-beam *h* is an arm, *y*, at the end of which is a friction-roll, *z*, resting upon the wheel *o*, in line with the groove *v*, in such manner that as each piece *w* (in the rotation of the wheel) comes into contact with this roll, it raises the roll and thereby the beam, (as will readily be seen,) and, in raising the beam,

lifts the points of the pens from the surface of the cylinder b , and thereby arrests the ruling, while, as each lifter-piece passes the segment, the roll drops down upon the surface of the wheel, and thereby lets the pens down again to the cylinder, so that while a sheet of paper is passing under the pens, they will automatically rule, and stop ruling, accordingly as they are thrown up and let down by means of the wheel o and its segment-pieces w . These pieces are made movable, and by joining them together or lapping them, the length of space traversed by the cylinder o , and the paper thereon, while the pens are raised from the paper, and while they are let down thereupon, may be regulated as may be desirable.

To throw the wheel o out of action when the sheet of paper has passed, and into action as a fresh sheet enters, a mechanism is employed as follows:

Over the pen-beam h is a horizontal rod, a' , having, near one end, an arm, b' , jointed to a latch-lever, c' which lever turns on a fulcrum at d' , the opposite end of the lever having a hook, e' , which hook rests upon the surface of the wheel o , being held normally down to same by a spring, or by other suitable means.

A pin, g' , projects up from this wheel, and as in the rotation of the wheel o this pin g' comes round to the hook e' , the hook catches the pin and stops the wheel, and if a segment-piece, w , is opposite to the wheel, it will be obvious that this stoppage takes place when the pens are raised from the paper, they being kept raised until the wheel shall be released from the hook e' . The rod a' also has fixed to it an arm, h' , at the foot of which is a sort of cam-shaped roll, i' , turning in a fork in the foot. This roll has a flat or but slightly-curved face, k' , on one edge of it, and adjacent to one end of this face a notch, l' , the lower edge of the notch coming down to an edge with the end of the face k' , and from this notch over to the opposite end of the roll the surface of the roll is rounded, so as to roll freely by friction with the moving surface of the cylinder.

Now, when the wheel o has been thrown out of action by the hook e' , the face k' of the roll i' lies upon the cylinder, as seen in the detail, D. As the edge of the advancing sheet of paper strikes the edge of this face, it slides up into the notch, and then, by its pressure against the roll, it tips it up, as seen by the dotted lines at D, thereby raising the arm h' and slightly turning the rod a' in its bearings, which movement of the rod presses down the link, which connects the arm b' to the latch-lever c' , and thereby raises the opposite or hooked end of said lever, and releases the pin g' , the wheel o being then free to move on and to effect the alternate ruling and spacing upon this sheet as upon the last one. The movement of the edge of the paper against the cam-roll upsets the roll and brings its curved surface over upon the paper, and the roll will then rotate by the contact of the paper until its flat surface comes down upon the paper, when it will stop, being then in position to be similarly operated upon by the edge of the next sheet of paper.

1. I claim combining, with a ruling-mechanism, the wheel o , provided with lifter-surfaces or pieces, for effecting the rise of the pens at the proper times, when the wheel is arranged in relation to the ruling-cylinder, substantially as described.
2. I also claim making the lifter-pieces w adjustable within the circular grooves v , when held in position, substantially as set forth.
3. I also claim arranging the wheel o with its axis at right angles to that of the ruling-cylinder or bed, so as to be driven by frictional contact therewith, substantially as set forth.
4. I also claim combining, with the wheel o and cylinder b , arranged in relation to each other, substantially as described, mechanism for arresting the rotation of the wheel, and for effecting its release, substantially as and for the purpose specified.

CHAS. F. WEST.
